UNITED STATES PATENT OFFICE.

FRANK OBERST, OF NEW YORK, N. Y., ASSIGNOR, BY MESNE ASSIGNMENTS, TO SONORA PHONOGRAPH COMPANY, INC., A CORPORATION OF NEW YORK.

AUTOMATIC STOP.

Application filed February 21, 1923. Serial No. 620,471.

To all whom it may concern:

Be it known that I, FRANK OBERST, a subject of the Kingdom of Rumania, and a resident of the borough of Queens, county 5 of Queens, State of New York, have invented a certain new and useful Improvement in Automatic Stops, of which the following is a specification.

This invention relates to automatic stops 10 for phonographs and is designed to stop the rotation of the turntable when a record has been played completely. It is the object of this invention to provide a stop of the type described, which is simple in construction, 15 comprises a minimum number of parts, and is certain in its operation.

Records differ in the size of the unrecorded space, and it is therefore necessary 20 to provide for stopping the turntable when the tone arm is at various distances from the center of the record and turntable. For this purpose, this invention contemplates the provision of an adjustable member 25 adapted to be carried by the tone arm and capable of being adjusted for various sized records, and which is adapted to operate the stop mechanism when the needle reaches the innermost recording groove of a record irrespective of the distance of said groove 30 from the center of the turntable.

With these and other objects in view, to be more fully set forth hereinafter, the invention consists in the novel construction, combination of elements, and arrangement 35 of parts which will be exemplified in the operation and construction hereinafter described in the following specification and illustrated in the accompanying drawings, considered together or separately.

The inventive idea involved is capable 40 of receiving a variety of mechanical expressions, some of which, for the purpose of illustration, are shown in the accompanying drawings.

The invention will first be described in 45 connection with the accompanying drawings, illustrating one embodiment of the invention, wherein similar reference characters are used to designate corresponding 50 parts throughout the several views, and then more specifically defined and indicated in the appended claims.

In the accompanying drawings:—

Fig. 1 is a plan view of the phonograph 55 showing a record in position upon the turn-

table, the tone arm in the innermost groove of the record, and the relative positions of the automatic stop and stop actuating means.

Fig. 2 is an enlarged view of the stop mechanism per se, showing the stop in effective and ineffective positions. 60

Fig. 3 is an end view of the stop mechanism showing a portion of the turntable in section.

Fig. 4 is a plan view of a portion of the tone arm showing the stop actuating means in position thereon. 65

Fig. 5 is an end view of the device shown in Fig. 4.

Referring to the drawings, there is shown 70 a phonograph comprising a casing 10 and a turntable 11 having a record 12 thereon. The impressed portion of said record is provided with spiral grooves and enclosed between the outermost groove or circle of 75 impressions or spiral grooves 13 and the innermost groove or circle of impressions 14. The phonograph is provided with the usual pivoted tone arm 15 carrying at its forward end a reproducer or sound box 16 80 and stylus 17 adapted to operate in the grooves of the record. The turntable is mounted upon a spindle 20 adapted to be driven by spring motor (not shown). Said motor normally tends to rotate the turntable as long as the spring is under any tension, and in order to stop the turntable either manually or automatically, there is provided the stop mechanism shown enlarged in Fig. 2. Said stop mechanism 85

comprises a friction member in the form of a lever 25 pivoted upon a plate 26 at 27, said plate 26 being fixed to the motor board 30 in any suitable manner, as by screws passing through openings 31. The lever 25

is provided with an arm 32 which carries a friction member such as a felt pad 33 at its end, so that as the lever 25 is moved clockwise to the dotted line positioned in 100 Fig. 2, the friction member will engage the depending flange 35 of the turntable to prevent rotation, and when said lever 25 is moved in the opposite direction to the full line position in Fig. 2, said turntable will be free to rotate. The lever 25 is normally urged in clockwise direction by means of a spring 36 fixed at one end to an arm 37

integral with said lever 25, said spring being fixed at its other end to a projection 38 upon a pawl member or lever 40 pivoted 105 upon a pawl member or lever 40 pivoted 110

upon plate 26 at 41. Said spring normally tends to rotate lever 40 in a clockwise direction to move a pawl 42 at one end of lever 40 into engagement with an arcuate surface 43 at the adjacent end of lever 25, said arcuate surface being provided with a notch 45 into which said pawl 42 is adapted to lodge when said lever 25 is moved counterclockwise to the ineffective position. Since 5 the spring 36 normally tends to rotate member 40 clockwise, the pawl 42 will be maintained in contact with arcuate surface 43 and when said lever 25 is moved to ineffective position against the action of said 10 spring 36, the pawl 42 will be forced into the notch 45 to lock said lever 25 in ineffective position to permit the turntable to rotate freely. The edge of the pawl 42, which 15 engages the lever 25 to hold it in ineffective position, is slightly beveled or cammed as shown at 40, so that by applying manual force to turn the lever 25 clockwise, the pawl 42 can be cammed outwardly, that is, to rotate lever 40 counterclockwise against 20 the action of spring 36 and permit member 33 to engage flange 35 and stop the rotation 25 of the turntable.

The releasing of friction member 33 from 30 ineffective position to stop the rotation of the turntable, may be accomplished automatically when a record has been completely played, by extending pawl member 40 rearwardly beyond the turntable, and providing 35 it with a stop or pin 50 in the path of the tone arm, so that when the stylus 17 is operating in the innermost groove of the record, the arm will engage stop 50 and rotate pawl member 40 counterclockwise to release pawl 42 from groove 45 and enable the 40 member 33 to stop the rotation of the turntable. It will be apparent that but a very slight movement of pawl member 40 is necessary to release pawl 42, that shown in the 45 drawing between the full line and the dotted line positions in Fig. 2 being ample for the purpose. If the pin 50 were in each case to be engaged by the tone arm proper, it is quite apparent that the various records having 50 different central smooth or unrecorded portions between the axis of the spindle and the innermost groove, would not be effective in all cases, and would stop the turntable in many cases too soon, and in other cases, not soon enough. For this purpose, there is 55 provided an adjustable member carried by the tone arm, which can be so set before the record is played, as to engage pin 50 at the proper time, regardless of the distance from the center of the innermost groove of the record. For this purpose, the tone arm is 60 provided with a lug 52 in which is pivotally and frictionally mounted an arm 53 having a bent-off portion 54 enabling it to extend downwardly to a point below the turntable. 65 It is quite obvious that by properly posi-

tioning the arm 53 relative to the pin 50, the automatic stop mechanism may be operated at will in any position of the stylus 17. Since the arm 53 operates below the turntable and may in some cases be inaccessible because positioned temporarily beneath the tone arm, there is provided on the motor board 30 a stop 56 in the path of arm 53, so that if said tone arm is moved outwardly (rearwardly to the dotted line position in Fig. 1) before setting, said arm 53 will engage pin 56 and be held in that position while the tone arm moves beyond said pin, thus rendering said arm 53 accessible. The tone arm is then moved 70 inwardly until the stylus 17 is in the last or innermost groove, the arm 53 meanwhile resting against pin 50 of the pawl member during the latter part of the inward movement of the tone arm. By this 75 means it is assured that as soon as the stylus reaches the innermost groove 14 the arm 53 will engage pin 50 to operate the stop mechanism. The tone arm is then lifted off, the 80 turntable is allowed to rotate by operating lever 25 and the stylus 17 is placed in the outermost groove 13. It is apparent that when the record has been played until stylus 85 17 is in the last groove, arm 53 will contact with pin 50 to rotate the pawl member 90 slightly counterclockwise and actuate the 95 stop mechanism.

Upon plate 26 is provided an upstanding lug 60 through which passes an adjustable set screw 61 adapted to contact with an upstanding lug 62 upon pawl member 40 when 100 said pawl member is moved counterclockwise a predetermined distance, thus limiting the counterclockwise movement of lever 40 and preventing undue stretching of spring 36. 105

In accordance with the provisions of the Patent Statute, I have described the principle of my invention together with the apparatus which I now consider to represent the best embodiment thereof, but I desire it 110 understood that my invention is not confined to the particular form of apparatus herein shown and described, the same being merely illustrative, and that the invention can be carried out in other ways without departing from the spirit of my invention, and, therefore, I claim broadly the right to employ all equivalent instrumentalities coming 115 within the scope of the appended claims, and by means of which objects of my invention 120 are attained, and the new results accomplished, as herein set forth, as it is obvious that the particular embodiments herein shown and described are only some of many that can be employed to attain these objects 125 and accomplish these results.

I claim:

1. In a sound reproducing device having a swinging tone arm, a turntable to carry records and a motor to revolve said turn- 130

table, an automatic stop comprising a pivoted friction member adapted to make contact with said turntable to prevent rotation thereof, means tending to rotate said friction member to effective position, a pivoted pawl engaging said friction member to hold said friction member in ineffective position, means traveling with the tone arm and adapted to engage said pawl to cause it to release said friction member, and means to hold said engaging member away from the tone arm when the latter is in its initial playing position.

2. In a sound reproducing apparatus having a swinging tone arm, a motor board, a turntable to carry records and a motor to revolve said turntable, an automatic stop comprising a pivoted friction member adapted to make contact with said turntable to prevent rotation thereof, means tending to rotate said friction member to effective position, a pivoted pawl engaging said friction member to hold said friction member in ineffective position, an arm traveling with said tone arm and adapted to engage said pawl to cause it to release said friction member,

and means carried by the motor board to arrest the travel of said arm and hold it clear of the tone arm when the latter is swung to initial playing position.

3. In a sound reproducing device having a swinging tone arm, a motor board, a turntable to carry records and motor to revolve said turntable, an automatic stop comprising a pivoted friction member adapted to make contact with said turntable to prevent rotation thereof, means tending to rotate said friction member to effective position, a pivoted pawl engaging said friction member to hold said friction member in ineffective position, an arm traveling with said tone arm and adapted to engage said pawl to cause it to release said friction member, and an abutment on the motor board permitting passage of the tone arm but arresting movement of said arm to hold said arm clear of the tone arm when the latter is swung to initial playing position.

This specification signed this 9th day of February, 1923.

FRANK OBERST.
